CUTTING KNIFE SUPPORT

Albert F. Shields, Jamaica, N. Y., assignor to S. & S. Corrugated Paper Machinery Co., Inc., Brooklyn, N. Y., a corporation of New York

Application February 10, 1940, Serial No. 318,293

4 Claims. (Cl. 164—68)

This invention relates to cutting knife mechanisms and more particularly to supports therefor, including supports for mechanism operable therewith.

In the manufacture of corrugated sheet material, it is frequently necessary to cut such sheet material into predetermined sections of standard length. This is most frequently done as the corrugated web comes from the machines which manufacture the same, the web led from these machines being cut to the proper width.

It is customary therefore to place the cutting machine at the terminus of the corrugated web manufacturing line so that the end product of the entire manufacturing process is a series of corrugated sheets of predetermined standard length. The cutting machines for this purpose are complicated and heavy while nevertheless requiring delicacy of adjustment. Thus, for instance, the same machine with the same cutting knives may, by simple adjustments, such as that shown in applications Nos. 320,471 filed Feb. 24, 1940, 318,294, filed Feb. 10, 1940 and Patent No. 2,208,350 and Patent No. 2,202,872 all of which are assigned to the assignee of this application, be arranged to cut sheets of varying lengths without interfering with or slowing down or changing the speed of movement of the corrugated web as it comes from the prior manufacturing processes.

That is, a machine which is cutting sheets 120" in length may by a simple adjustment be changed to cut sheets of 90", 60", 30" or any other dimension. In all cases, the cutting knives are driven primarily through a Reeves drive mechanism which varies the average speed of rotation of the cutting knife with respect to the corrugated web so as to produce a cutting operation at a selected interval for the purpose of producing a sheet of the selected length. And, in addition and working with the Reeves drive or adjustable at the same time as the Reeves drive, either automatically or manually, other apparatus adds a cyclic variation in the speed of rotation of the cutting knives so that whatever the average speed of rotation thereof, the cutting knives will be traveling at the speed of the web during the actual cutting.

Since the Reeves drive itself and the various adjustments and the drums or shafts carrying the cutting knives are continuously rotating and frequently being varied in their adjustments and since the cutting knives themselves and all of the rest of the machinery including the Reeves drive is periodically subjected to increased strain

when the knives pass through the corrugated web, the machine itself must be sturdily and rigidly constructed and all parts thereof should as far as possible be interbraced and rigidified.

5 Heretofore, in cutting machines of this type, the elements thereof have to a great extent been separated or dispersed. Thus the Reeves drive which transmits power to the rotating cutting knives, and which is subjected to the greatest 10 stresses, being driven at one end from the power source and at the other being subjected to the vibration and the periodic load of the passing of the knife through the sheet, has always been not so much a part of the machine integrated and 15 unitary therewith, but rather an attachment thereto, to be placed in any desired position with respect thereto as space requirement provided. Also the input driving mechanism such as gears or chains and other apparatus have hitherto been 20 separately housed or detached from the main body of the machine in some way.

The vibration entailed in the operation of the machine and the heavy periodic loads have frequently caused minor disarrangements of the 25 Reeves drive and interrelated mechanism which, while not serious in themselves, nevertheless hasten the wear of the entire machine and also caused continued inconvenience in that frequent readjustments were necessary.

30 A principal object of this invention therefore is to integrate the entire assembly necessary for the cutting of the continuously traveling corrugated web. That is, to combine in a single unitary apparatus, which is interbraced, all of 35 the elements necessary for the operation.

A further object of this invention is to arrange the Reeves drive so that it may be mounted within the apparatus itself and so that it may be protected by its mounting therein and be so arranged that vibratory forces and periodic changes in the load can have no effect on the adjustment or arrangement thereof.

Further objects of this invention are to cross 45 brace and interbrace the entire apparatus along its outer surface in such a way that it presents the appearance of a single unitary structure, the parts thereof being accessible for adjustment and repair but the entire apparatus having nevertheless a completed and finished appearance 50 and being protected.

Further objects and uses of this invention will in part be apparent and in part pointed out in the following description and drawings, in which:

55 Figure 1 is a view in perspective of a duplex

cutting machine made in accordance with my invention.

Figure 2 is a cross-sectional view taken on line 2-2 of Figure 1 and is also a cross-sectional view taken on line 2-2 of Figure 3.

Figure 3 is a cross-sectional view taken on line 3-3 of Figure 2.

Referring now to Figures 1, 2 and 3, I have here shown a duplex cutting machine capable of operating upon two separate webs at the same time. The machine comprises cutting knives 10 and 11 respectively mounted on shafts 12 and 13 to interengage with each other once during each revolution of shaft 12 and 13 in order to sever the corrugated sheet material passing therethrough. The machine also comprises cutting knives 14 and 15, each respectively mounted on the drums or shafts 16 and 17 in order to periodically cut a second web passing therebetween.

Referring specifically to Figure 2, the web of sheet material when it is received from the prior manufacturing processes may be fed by the conveyor belt 18 into and between the shafts 12 and 13 on to the platform or bed 19. The forward edge of the web, as it is thrust forward, passes between the feed rollers 20 and 21 which continue to carry it forward onto the bed 22. The cutting knives 10 and 11 are arranged to cut the web material at any selected interval after the forward edge thereof has passed between the feed rollers 20 and 21.

The sheet after it has been cut by the knives 10 and 11 nevertheless remains under the influence of feed rollers 20 and 21 and is forced forward on the bed 22 where it may be manually removed or the bed 22 may be so short that the forward rollers 20 and 21 may feed the cut sheet so that its center of gravity extends beyond the edge of the bed 22 so that it may fall off when it has left the feed rollers thus leaving the bed free for the next sheet. The operation is exactly the same with respect to cutting knives 14 and 15 and their associated feed belt 24, bed 25, feed rolls 26, 27 and 28.

A single power source may, as is clear, be used for the operation of both cutting knives. As is seen in Figures 1 and 3, power is transmitted from the power shaft 29 through the bevel gears 30 and 31 to the shaft 32. Gear 33 keyed to shaft 32 meshes with gear 34 keyed to shaft 35 and thereby operates one of the members 36 of the Reeves drive 37. This Reeves drive through the shaft 38 and appropriate gearing and connecting mechanism contained in the housing 39 operates one of the cutting knife assemblies, for instance, knives 10 and 11.

Gear 40 keyed to shaft 32 meshes with gear 41 keyed to shaft 42 of the Reeves drive mechanism 43 which in turn through the shafts 44 operates mechanism housed in the housing 45 and controlling and operating the other set of cutting knives, to wit, knives 14 and 15.

Other mechanism such as that shown in patents and applications above mentioned for varying the adjustments of the cutting knives, for varying the adjustments of the Reeves drive, and for integrating the adjustments of the Reeves drive and the cyclical adjustments of the cutting knives may be housed in either housing 39 and 45.

These members are not shown since they are not necessary to the present disclosure, it being sufficient to point out that the Reeves drive is connected to and is part of the power chain operating the cutting knives. Instead of mounting the Reeves drive as an attachment to the ma-

chine or outside the machine or in any indeterminate relation to the present machine, the Reeves drive of the present invention has been made an integral part of the machine itself encased within the covering of the machine and supported on bracing structures which themselves form part of the machine.

Thus the housings which house the associated mechanism are themselves supported on base 46, being riveted, welded or otherwise securely affixed thereto in any suitable manner.

Also the main driving gears 30 and 31, together with their respective shafts and supporting bearings are seen to be housed completely within the main housing where they run in the same oil bath with the housing gears.

The base 46 comprises also a platform 47 (Figure 2) carrying supporting flanges 48 and 49 cast or integral therewith.

Brace 50 comprises main portion 51 and base portion 52 and is securely attached to the platform 47 by bolts or rivets 53 passing through flanges 54 of said brace 50. The brace 51 also comprises integral lateral flanges 55 (Figure 3) which are by means of bolts 56 securely attached to the housings 39 and 45.

Top brace 58 is a flanged member which may by bolts 59 be connected between the housings along the top of the apparatus.

The brace 58 therefore securely integrates the housings 39 and 45 spacing them rigidly and even assisting in binding them to their base.

A similar brace 57 (Figures 1, 2 and 3) constitutes the entire front of the machine and comprises a principal front member 58 having lateral flanges 59 and 60 which are bolted securely by bolts 61 and 62 to the end pillars 39 and 45. This brace 57 also has bottom flange 63 which is bolted securely by bolts or rivets 64 to the base 47.

In this manner by means of braces 58 and 57, the housings 39 and 45 are combined into a single unitary homogeneous entity efficiently cross-braced to prevent any shifting or vibration of any part of the mechanism relative to any other part. The brace 57 may have openings 65 therein covered by removable members 66 to provide for ready access to the interior of the member for adjustment, cleaning, repair or other purposes.

The rear brace 50 has L-shaped protrusions 67, 68 therefrom preferably integral with the brace 50 and extending into the interior of the machine (see Figures 2 and 3). Likewise the brace 57 has similar L-shaped projections 69, 70 extending into the interior of the machine and directly opposite the protrusions 67.

Cross-bracing members 69 and 70 are mounted between each pair of L-shaped members 67 and 68, being secured thereto by means of bolts 71 passing through the respective flanges of the members 69 and 70 and the members 67 and 68. This serves further to rigidly interbrace and cross-brace the entire mechanism.

The Reeves drives 37 and 43 are mounted within this rigidly cross-braced and interbraced frame. As will be seen, the shafts 38 and 39 of Reeves drive 37 are effectively supported between the cross-brace 69 and the housing 39 and the shafts 44 and 42 of the Reeves drive 43 are effectively supported between the cross-brace 70 and the housing 45.

In this manner, the Reeves drive is made an integral part of the mechanism, is rigidly mounted within an interbracing, rigidifying frame-

work of the mechanism, is no longer an appendage to the mechanism but an essential and homogeneous part thereof.

The Reeves drives cannot shift with respect to the mechanism by reason of its rigid and braced support, is no longer subjected to the various disadjustments which arise from uninhibited vibration, and is rigidly held in such manner that it cannot shift or become disadjusted by reason of the variations in loads imposed thereon.

It may be noted that as seen in Figures 1 and 3, the power source 29 may be connected through the opening 12 which in these illustrations is shown covered over and protected, the only change necessary in such case being the addition of a beveled gear similar to the beveled gear 31 at the end of the shaft 32 opposite the opening 12.

In this way, an additional power source may be, if desired, connected to the mechanism or if for any reason it seems desirable the mechanism or the power source may be shifted so that power is received from the opposite side of the machine.

The essential element, therefore, of this invention is the cross-bracing and interbracing of the entire machine, the mounting of the Reeves drive, power and input drive mechanisms not as appendages to the machine but as integral parts of the machine, the cross-bracing and support of the Reeves drive in the machine and the improvement in the appearance of the machine by means of the cross-bracing forming the outer walls of the machine and interbracing which presents a mechanism having a solid complete unitary appearance and one in which the various portions and mechanisms thereof are fully protected.

While I have shown in the foregoing description, a duplex cutting machine comprising two pairs of cutting knives and suitable apparatus for each set, it will be obvious that the present invention will readily be utilized in a simplex cutting machine and indeed has been found to be at least as practicable commercially in such an apparatus. Other means of bracing and arranging the various portions of the apparatus in the manner herein described will now be clear to those skilled in the art and I therefore prefer to be limited not by the disclosure herein, but only by the appended claims.

I claim:

1. A duplex cutting apparatus for cutting successive sheets from a pair of continuous webs, said apparatus comprising two sets of rotating cutting knives and means individual to each of said sets for adjusting the speed of rotation thereof, said sets of cutting knives being mounted between end housings of said apparatus, said adjusting means including a Reeves drive for each of said sets, a power connection from a power source to the Reeves drive of each of said sets, and a power connection from the Reeves drive to said cutting knives, a front brace between said end housings, said brace substantially enclosing the front of the apparatus, a rear brace between said end housings, said rear brace substantially enclosing the rear of the apparatus, the Reeves drive of each of said sets being supported by a cross brace extending between said front and rear braces and comprising a support for one side of the Reeves drive within the apparatus, the opposite sides of each of said Reeves drives being supported in end housings.

2. A duplex cutting apparatus for cutting successive sheets from a pair of continuous webs, said apparatus comprising two sets of rotating cutting knives and means individual to each of said sets for adjusting the speed of rotation thereof, said sets of cutting knives being mounted between end housings of said apparatus, said adjusting means including a Reeves drive for each of said sets, a power connection from a power source to the Reeves drive of each of said sets, and a power connection from the Reeves drive to said cutting knives, a front brace between said end housings, said brace substantially enclosing the front of the apparatus, a rear brace between said end housings, said rear brace substantially enclosing the rear of the apparatus, the Reeves drive of each of said sets being supported by a cross brace extending between said front and rear braces and comprising a support for one side of the Reeves drive within the apparatus, the opposite sides of each of said Reeves drive being supported in end housings, the power connection to each Reeves drive and the power connection from each Reeves drive to its respective set of cutting knives being housed in an individual end housing.

3. A duplex cutting apparatus for cutting successive sheets from a pair of continuous webs, said apparatus comprising two sets of rotating cutting knives and means individual to each of said sets for adjusting the speed of rotation thereof, said sets of cutting knives being mounted between end housings of said apparatus, said adjusting means including a Reeves drive for each of said sets, a power connection from a power source to the Reeves drive of each of said sets, and a power connection from the Reeves drive to said cutting knives, a front brace between said end housings, said brace substantially enclosing the front of the apparatus, a rear brace between said end housings, said rear brace substantially enclosing the rear of the apparatus, the Reeves drive of each of said sets being supported by a cross brace extending between said front and rear braces and comprising a support for one side of the Reeves drive within the apparatus, the opposite sides of each of said Reeves drives being supported in end housings, the power connection to each Reeves drive and the power connection from each Reeves drive to its respective set of cutting knives being housed in an individual end housing, said power connection to each Reeves drive comprising a rotatable shaft, gear connections from said rotatable shaft to each Reeves drive, said rotatable shaft being mounted between said end housings.

4. A duplex cutting apparatus for cutting successive sheets from a pair of continuous webs, said apparatus comprising two sets of rotating cutting knives and means individual to each of said sets for adjusting the speed of rotation thereof, said sets of cutting knives being mounted between end housings of said apparatus, said adjusting means including a Reeves drive for each of said sets, a power connection from a power source to the Reeves drive of each of said sets, and a power connection from the Reeves drive to said cutting knives, a front brace between said end housings, said brace substantially enclosing the front of the apparatus, a rear brace between said end housings, said rear brace substantially enclosing the rear of the apparatus, the Reeves drive of each of said sets being supported by a cross brace extending between said front and rear braces and comprising a support for one side of the Reeves drive within the apparatus, the opposite sides of each of said Reeves drives being supported in end housings.

for one side of the Reeves drive within the apparatus, the opposite sides of each of said Reeves drives being supported in end housings, the power connection to each Reeves drive and the power connection from each Reeves drive to its respective set of cutting knives being housed in an individual end housing, said power connection to

each Reeves drive comprising a rotatable shaft, gear connections from said rotatable shaft to each Reeves drive, said rotatable shaft being mounted between said end housings, and means for connecting said rotatable shaft to a power source at either housing.

ALBERT F. SHIELDS.
